REFRIGERATION

Jesse G. King, Dayton, Ohio, assignor to Frigidaire Corporation, Dayton, Ohio, a corporation of Delaware

Application June 3, 1933, Serial No. 674,240

11 Claims. (Cl. 62—141)

This invention relates to refrigeration.

This invention is directed to the cooling of liquid such as beer, carbonated beverages, water and the like and is particularly directed to an apparatus which may be given an ornamental finish, and is adapted to be placed and displayed at the bar, soda fountain or other place where cold drinks are dispensed. This invention is directed to a construction which increases the cooling efficiency of such an apparatus, so that it may be made more compact and thus require less room where space is of extreme value.

Further objects and advantages of the present invention will be apparent from the following description, reference being had to the accompanying drawings, wherein a preferred form of the present invention is clearly shown.

In the drawings:

Fig. 1 is a view, partly in vertical cross-section, and partly diagrammatic of an apparatus embodying features of this invention;

Fig. 2 is an enlarged horizontal cross-sectional view taken along the line 2—2 of Fig. 1; and

Fig. 3 is an enlarged horizontal view taken along the line 3—3 of Fig. 1.

An apparatus embodying features of my invention includes, in general, a refrigerant casing 10, in which a body of liquid refrigerant 11 is maintained by a suitable apparatus hereafter to be more fully described. A chamber 12, for liquid to be cooled, is so disposed with respect to the refrigerant casing 10, that at least one of its surfaces 13, is exposed to the body of liquid refrigerant 11. Preferably, as shown in this modification, the chamber 12 is wholly disposed within the casing 10, so that all of its sides are submerged in the liquid refrigerant. The chamber 12 is provided with a liquid inlet fixture 14 and with a liquid outlet fixture 15, the outlet extending upwardly by means of a pipe 16 to a point near the top of the chamber 12. The outlets 14 and 15 are connected respectively with the pipes 17 and faucet 18, so that the liquid, such as beer from the barrel 19, enters the chamber 12 at 14, is cooled therein, and is discharged through the pipe 16, outlet 15 and faucet 18.

The apparatus is provided with means for liquefying and returning refrigerant which is evaporated from the body 11 of liquid refrigerant. In this particular embodiment, this means includes a refrigerant liquefying unit, generally designated as 20, which unit withdraws evaporated refrigerant from the casing 10 through the outlet pipe 21, valve fixture 22, pipe 23, from which pipe the evaporated refrigerant enters the lique-

fying unit 20. The liquefied refrigerant is delivered through the pipe 24 through a float-controlled valve 25, which admits the liquid refrigerant into the body 11, the float 26 maintaining a substantially constant level of refrigerant in the casing 10. In this particular embodiment, the refrigerant liquefying unit 20 includes a compressor 27 which delivers compressed refrigerant to a condenser 28, which discharges liquefied refrigerant to the receiver 29 from whence refrigerant flows through the pipe 24 and fixture 25 into the casing 10. The compressor 27 is driven by an electric motor 30.

An automatic control is provided to maintain the body 11 of liquid refrigerant within predetermined temperature limits. In this particular embodiment, this control includes a bellows 31 responsive to the vapor-pressure, or temperature, characteristics of the body 11 of liquid refrigerant. This is accomplished by connecting the bellows 31 to the evaporated refrigerant line 23. The bellows 31 actuates a snap switch 32 which starts and stops the motor 30 in accordance with the vapor-pressure, or temperature, characteristics of the body 11 and maintains the body within predetermined temperature limits in accordance with the adjustment of the snap switch 32. The snap switch 32 may be adjusted to maintain the body 11 a few degrees colder than the temperature desired for the liquid to be cooled which is discharged through the faucet 18 to compensate for the heat exchange gradient of the chamber 12.

The chamber 12 is constructed in a manner to enhance the efficiency of the apparatus and to increase thermal exchange between the liquid within the chamber 12 and the liquid refrigerant 11. To this end, the chamber 12 is provided with a plurality of pipes 33 which extend into the chamber 12 from the body 11 of liquid refrigerant. Preferably these pipes 33 are in the form of depending duct loops which extend downwardly and are formed into loops by the U construction 34 as indicated in Fig. 1. By this construction, the chamber 12 can be made in the form of a vertical cylinder, having bottom 35 secured to the vertical wall by the spun construction 36 as indicated in Fig. 1. The inlet and outlet fittings 14 and 15 may be secured by soldering or brazing them to the bottom 35 before the top or wall 13 is secured to the cylindrical vertical sides 37. The top 13 has secured thereto the depending duct loops 33, properly brazed or soldered, and thereafter the top 13 is secured to the sides 37 by the spun construction 38 indicated in Fig. 1. Prefer-

ably the seams at 36 and 38 are also brazed or soldered.

The construction above described, permits liquid refrigerant to enter the duct loops 33 by gravity, and when uncooled liquid entering the chamber 12, the violent evaporation or evolution in the tubes 33 creates an efficient thermal exchange between the liquid inside of the chamber 12 not only through the outer walls of the chamber 12 but also through the tubes or duct loops 33. Because the open tops of the duct loops are submerged and the duct loops are vertical they are maintained in a flooded condition with liquid refrigerant. This construction greatly enhances the thermal exchange capacity of the apparatus and permits a smaller construction than has heretofore been possible.

The casing 10 is preferably made by providing a cylindrical plated shell 40 to which a plated dome 41 may be soldered or brazed. The casing 10 is supported on the platform 42 which is secured to the plated stand-pipe 43 having a pedestal 44 adapted to rest on the bar, soda fountain or the like. The outlet fixture 15 at its lower end 25 has a flange 15a, under which is placed the gasket 15b. The flange 15a is secured to the platform by screws, not shown, passing upwardly through the platform into threaded engagement with the holes 15c in the flange 15a. Also two or more internally threaded supporting fins 45 which are soldered to the casing 10 are bolted to the platform 42 in a similar manner by bolts or screws 46. By this construction a very ornamental plated construction can be provided, in which all of the exposed parts can be readily plated, and, when so plated, they present a very pleasing appearance.

While the form of embodiment of the invention as herein disclosed, constitutes a preferred form, it is to be understood that other forms might be adopted, all coming within the scope of the claims which follow.

What is claimed is as follows:

1. In a refrigerating apparatus, in combination, a refrigerant casing, a body of volatile liquid refrigerant in said casing, a chamber for liquid to be cooled having a surface exposed to said body of liquid refrigerant, ducts extending into said chamber from said body of liquid refrigerant, inlet and outlet connections on said chamber for liquid to be cooled and means for reducing the pressure on said liquid refrigerant to cause it to volatilize at liquid cooling temperatures.

2. In a refrigerating apparatus, in combination, a refrigerant casing, a body of volatile liquid refrigerant in said casing, a chamber for liquid to be cooled having a surface exposed to said body of liquid refrigerant, ducts depending into said chamber from said body of liquid refrigerant, inlet and outlet connections on said chamber for liquid to be cooled and means for reducing the pressure on said liquid refrigerant to cause it to volatilize at liquid cooling temperatures.

3. In a refrigerating apparatus, in combination, a refrigerant casing, a body of volatile liquid refrigerant in said casing, a chamber for liquid to be cooled having a surface exposed to said body of liquid refrigerant, duct loops depending into said chamber from said body of liquid refrigerant, inlet and outlet connections on said chamber for liquid to be cooled and means for reducing the pressure on said liquid refrigerant to cause it to volatilize at liquid cooling temperatures.

4. In a refrigerating apparatus, in combination, a refrigerant casing, a body of volatile liquid refrigerant in said casing, means for reliquefying

and returning refrigerant evaporated from said body of liquid refrigerant, a chamber for liquid to be cooled having a surface exposed to said body of liquid refrigerant, pipes extending into said chamber from said body of liquid refrigerant, and inlet and outlet connections on said chamber for liquid to be cooled.

5. In a refrigerating apparatus, in combination, a refrigerant casing, a body of volatile liquid refrigerant in said casing, means for reliquefying and returning refrigerant evaporated from said body of liquid refrigerant, an automatic control to maintain said body of liquid refrigerant within predetermined temperature limits, a chamber for liquid to be cooled having a surface exposed to said body of liquid refrigerant, pipes extending into said chamber from said body of liquid refrigerant, and inlet and outlet connections on said chamber for liquid to be cooled.

10. In a refrigerating apparatus, in combination, a refrigerant casing, a body of volatile liquid refrigerant in said casing, a chamber for liquid to be cooled having a surface exposed to said body of liquid refrigerant, pipes supported from said surface and extending into said chamber from said body of liquid refrigerant and means for reducing the pressure on said liquid refrigerant to cause it to volatilize at liquid cooling temperatures.

15. In a refrigerating apparatus, in combination, a refrigerant casing, a body of volatile liquid refrigerant in said casing, a chamber for liquid to be cooled having a surface exposed to said body of liquid refrigerant, duct loops depending and supported from said surface and extending into said chamber from said body of liquid refrigerant and means for reducing the pressure on said liquid refrigerant to cause it to volatilize at liquid cooling temperatures.

20. In a refrigerating apparatus, in combination, a vertically disposed refrigerant casing, a body of volatile liquid refrigerant in said casing, a chamber for liquid to be cooled disposed within said casing and submerged in said body of liquid refrigerant, said chamber having a top wall, pipes secured to said top wall and extending downwardly from said body of liquid refrigerant into said chamber, inlet and outlet connections for liquid to be cooled and means for reducing the pressure on said liquid refrigerant to cause it to 25 volatilize at liquid cooling temperatures.

25. In a refrigerating apparatus, in combination, a vertically disposed refrigerant casing, a body of volatile liquid refrigerant in said casing, a chamber for liquid to be cooled disposed within said casing and submerged in said body of liquid refrigerant, said chamber having a top wall, pipes secured to said top wall and extending downwardly from said body of liquid refrigerant into said chamber, inlet and outlet connections for 30 liquid to be cooled, and means for reliquefying and returning evaporated refrigerant from said body of liquid refrigerant.

35. In a refrigerating apparatus, in combination, a vertically disposed cylindrical refrigerant casing, means for maintaining a predetermined level of a body of volatile liquid refrigerant in said casing, a cylindrical chamber for liquid to be cooled disposed within said casing and submerged in said body of liquid refrigerant, said chamber having a top wall, pipes secured to said top wall and extending downwardly from said body of liquid refrigerant into said chamber, inlet and outlet connections for liquid to be cooled 40

and an evaporated refrigerant outlet above said level.

11. In a refrigerating apparatus, in combination, a vertically disposed cylindrical refrigerant 5 casing, means for maintaining a predetermined level of a body of volatile liquid refrigerant in said casing, a cylindrical chamber for liquid to be cooled disposed within said casing and sub-merged in said body of liquid refrigerant, said

chamber having a top wall, pipes secured to said top wall and extending downwardly from said body of liquid refrigerant into said chamber, inlet and outlet connections for liquid to be cooled, and an evaporated refrigerant outlet above said level means connected to said refrigerant outlet for reliquefying and returning evaporated refrigerant from said body of liquid refrigerant.

JESSE G. KING.
